UNITED STATES PATENT OFFICE

BRUNO BAUER, OF VIENNA, AUSTRIA

CAST-IRON CORE FOR THE PRODUCTION OF COLUMNS OF BRACED REINFORCED CONCRETE

Application filed September 10, 1927, Serial No. 218,638, and in Austria July 22, 1927.

This invention relates to a cast iron core for the production of columns of braced reinforced concrete.

The cast iron core according to the present invention consists of vertical ribs, which are provided with spiral-shaped notches for the reception of a wire winding and are enlarged to form consoles which serve as supports for the roof construction or as column feet.

Fig. 1 shows a longitudinal section of a four-part cast iron core.

Fig. 2 is a cross section thereof on A—A or B—B.

Fig. 3 is a cross section of an eight-part cast iron core on the same section lines,

Fig. 4 shows the use of a sliding shell and

Fig. 5 the use of a perforated sheet metal shell when concreting braced cast iron cores,

Fig. 6 shows a longitudinal section of another form of construction of braced cast iron cores.

In Fig. 7 is illustrated a cross section on C—C and in

Fig. 8 a cross section on D—D or E—E.

The ribs *a* which in the notches are provided with wire windings *b* are enlarged upwardly and form a console *c* serving as a support for roof beams *d*. In this form of construction the thrust of superposed cast iron cores takes place at the upper edge *e* of the consoles which forms the lower edge of the roof beams.

In the form of construction according to Fig. 6 each cast iron core is provided at its upper end with a sleeve like extension *f* of which the edge coincides with the upper edge of the roof beams and serves for the reception of the foot of the next column.

By reason of this construction it is possible that the next column need not be erected until the roof construction on the next lower column has been completed.

In this form of construction of the cast iron cores the part of the console from the foot end to the upper edge may be rendered normal or are standardized, whilst the part from the upper edge of the console to the upper edge of the sleeve forms a fitting piece.

In Fig. 4 the sliding shell is indicated by *g* and in Fig. 5 the perforated sheet metal used

as shell by *h*. The perforations in the sheet metal shell do not only enable the air to escape when concreting but also the passage of the concrete itself, whereby particularly intimate connection is effected between the shell and the concrete and a drying of the concrete is facilitated.

I claim—

1. As an article of manufacture a metallic core for the production of columns of braced reinforced concrete, comprising ribs, notches on the ribs, the notches of the several ribs being respectively vertically displaced, a bracing member disposed in the said notches and wound round the core formed by the said ribs, and an enlargement provided on the ribs in order to form a console, so that the thrust of superposed cast iron cores takes place at the upper edge of the consoles which forms the lower edge of the roof beams.

2. As an article of manufacture a metallic core for the production of columns of braced reinforced concrete, comprising ribs, helically disposed notches on the ribs, a bracing member disposed in the said notches and wound round the core formed by the said ribs, and a cupped extension provided at the upper end of the said core, the edge of the said enlargement coinciding with the upper edge of the roof beams and serving for the reception of the foot of the next column.

3. As an article of manufacture a metallic core for the production of columns of braced reinforced concrete, comprising ribs, helically disposed notches on the ribs, a bracing member disposed in the said notches and wound round the core formed by the ribs, an enlargement provided on the ribs in order to form a console, the part of the core from the foot end to the upper edge of the console being standardized, and a cupped extension fitted on top of the upper edge of the console.

4. As an article of manufacture a metallic iron core as claimed in claim 1, further comprising a perforated sheet metal shell arranged around the ribs.

5. As an article of manufacture a metallic core as claimed in claim 1, further comprising a perforated sheet metal shell arranged around the ribs.

6. As an article of manufacture a metallic core as claimed in claim 2, further comprising a perforated sheet metal shell arranged around the ribs.
- 5 7. A metallic core for the purpose specified, comprising a column having externally arranged ribs with notches therein, the ribs at the end of the column being of greater diameter than the rib at the other end and bracing wires engaged in said notches.
- 10 In testimony whereof I affix my signature.

DR. BRUNO BAUER.
